Daniel Barnes & Waelley.

UNITED STATES PATENT OFFICE.

RICHMOND LEVERING, OF NEW YORK, N. Y.

GAS-ENGINE.

No. 854,096.

Specification of Letters Patent.

Patented May 21, 1907.

Application filed January 16, 1907. Serial No. 352,478.

To all whom it may concern:

Be it known that I, RICHMOND LEVERING, a citizen of the United States, residing at the city, county, and State of New York, have invented certain new and useful Improvements in Gas-Engines, of which the following is a full, clear, and exact description.

My invention relates to improvements in gas engines, and involves the method of providing and supplying to the engine a suitable gas for internal combustion.

Heretofore only the more volatile hydrocarbons have been employed for this purpose with any degree of satisfaction in general practice. By my invention, however, kerosene or crude oil, for example, may be employed with entire satisfaction with greater efficiency and relatively less expense.

In the accompanying drawings I have shown conventionally my invention as applied to a four cylinder engine of the internal combustion type.

In said drawings Figure 1 is a diagrammatic view, partly in elevation and partly in section. Fig. 2 is a relatively enlarged view of details of construction, partly in section on the line X—X Fig. 1. Fig. 3 is a relatively enlarged sectional view on the plane of the line Y—Y Fig. 1.

1—1—1—1 represent four cylinders, the same being shown conventionally.

2 is a supply pipe having suitable branches leading to each cylinder.

3 represents an exhaust pipe in common to all the cylinders.

4 is a gas forming chamber directly adjacent to the exhaust pipe 3, and partitioned therefrom by the wall 5.

6 is a pipe arranged to convey liquid fuel from the tank or receiver K, which receiver may contain a suitable liquid fuel, for example kerosene. Projecting from the fuel supply pipe 6 into the gas forming chamber 4 are spraying nozzles 7 in any suitable number. One of these nozzles is shown in Fig. 2.

In the particular construction shown in the drawing, it would be preferable to have four nozzles, locating one directly in front of each exhaust outlet from the several cylinders.

As is well known, the hottest part of the exhaust pipe is directly where the exhaust gases emerge from the cylinder, and the greater efficiency can be obtained by having the spraying nozzles 7 so placed as to project any spray therefrom directly against the wall of the exhaust pipe 5 where the same is the hottest.

The gas forming chamber 4 is closed at one end and leads in a direction preferably to follow the exhaust pipe for a considerable distance. When fuel is forced through pipe 6, it emerges in a fine stream through the several nozzles 7. Upon encountering the hot wall 5 expansion takes place and it is converted into gas.

8 is a gas receiver or tank connected to the gas forming chamber 4 by a cooler 9 in which is located a suitable check valve 10. The increase of pressure within the gas forming chamber 4 will cause the gas therein to be forced past the check valve 10, through cooler 9 and into storage tank 8. When a sufficient quantity of gas has been stored in tank 8, and the pressure therein has risen to a predetermined point, a valve 11 will be forced open so that any excess pressure will be prevented. On the stem of this valve 11 may be another valve 12 which will prevent the escape of more gas than is desired. The opening of the valve 11 will move the valve stem in a direction to close a fuel supply valve 14 in the pipe 6. Hence from that moment the supply of fuel through the nozzles 7 will cease and the further generation of gas will be checked until valve 14 is again opened.

15 conventionally represents a spring by which the pressure at which the valve 11 will open may be governed.

16 represents a gas pipe having a valve 16^a therein, and leading from tank 8 to a mixer conventionally shown at M and of any desired form.

17 is a pipe having a valve 17^a therein. This pipe 17 is adapted to convey the mixture formed within the mixer M to the pipe 2.

C conventionally represents a carbureter.

G represents a tank containing, for example, gasolene or naphtha.

18 is a pipe, having a valve 18^a therein, leading from the tank G to the carbureter C.

19 is a pipe leading from the carbureter C to the supply pipe 2. 19^a is a valve therein. The liquid gasolene is conveyed through pipe 18 to the carbureter C, where it is mixed in any suitable way with the proper proportion of air to form an explosive mixture. This mixture is then conveyed through pipe 19 to the supply pipe 2.

In operation the engine is started, for example, by means of gasolene. The valves 18^a and 19^a being opened to the proper degree, while the valves 16^a and 17^a are closed. When the engine has been running a suffi-

cient time to properly heat the exhaust, the valve 14 is opened, whereupon the fuel from the tank K is forced into the chamber 4 where the gas is formed in the manner previously described. While the gas is in the chamber 4 (which is preferably continuous down to the check valve 10) it becomes an incondensable or fixed gas. This gas passes through the cooler 9 and into the receiving tank 8. When a sufficient quantity of gas is contained therein, the valves 18^a and 19^a may be closed and the valves 16^a and 17^a opened, the proper adjustments being assumed. The fixed gas will then be drawn through the mixer M and there mixed with a suitable proportion of air to form an explosive mixture which will be drawn as required into the several cylinders.

What I claim is:

- 20 1. In a gas engine, a cylinder, an exhaust pipe leading therefrom, a gas forming chamber adjacent to said exhaust but not in communication therewith, a fuel supply leading to the interior of said gas forming chamber, a gas storage reservoir connected to said gas forming chamber, a check valve between said reservoir and chamber, a connection leading from said storage reservoir to said cylinder, and a mixer in said connection.
- 25 2. In an engine of the internal combustion type, a cylinder, an exhaust pipe leading therefrom, a gas forming chamber adjacent to said pipe but not in communication therewith, a liquid fuel supply leading into said chamber, a gas receptacle, a gas cooler between said gas forming chamber and said receptacle and connecting the same, a check valve between said reservoir and chamber, a connection from said reservoir to said engine, and an air and gas mixer in said connection.
- 30 3. In an engine of the internal combustion type, a cylinder, an exhaust, a gas forming chamber, a gas cooler, a gas receiving tank, a connection from said tank to said cylinder, an air and gas mixer therein, a liquid fuel supply leading to said gas forming chamber, a valve therein, an outlet from said gas receiver, and a pressure controlling valve therein.
- 35 4. In an engine of the internal combustion type, a cylinder, an exhaust, a gas forming

chamber, a gas cooler, a gas receiving tank, a connection from said tank to said cylinder, an air and gas mixer therein, a liquid fuel supply leading to said gas forming chamber, a valve therein, an outlet from said gas receiver, a pressure controlling valve therein, and a connection between said last named valve and the valve in the liquid fuel supply pipe.

5. In an engine of the internal combustion type, a cylinder, an exhaust pipe leading therefrom, a gas forming chamber adjacent to said exhaust pipe, a valved liquid fuel supply leading thereto, means to project a spray of liquid fuel into said forming chamber and against the wall of the exhaust pipe, a continuation of said gas forming chamber following said exhaust pipe for a substantial distance, a gas receiving tank, a gas cooler connecting said tank with said gas forming chamber, a check valve therein, an air and gas mixer, a gas pipe leading from said gas tank to said mixer, and a mixture conveying pipe leading from said mixer to said cylinder.

6. In an engine of the internal combustion type, a cylinder, a gas forming chamber adjacent thereto and arranged to absorb heat from the explosions therein, a fuel pipe leading into said gas forming chamber, a gas storage reservoir, a connection between said gas forming chamber and said storage reservoir, a connection leading from said storage reservoir to the cylinder, and an air and gas mixer in said connection.

7. In an engine of the internal combustion type, a cylinder, a gas supply pipe and an exhaust pipe therefor, a gas forming chamber directly adjacent to said cylinder and arranged to absorb the heat of the explosions therein, a fuel pipe leading into said gas forming chamber, a gas storage reservoir, a connection between said chamber and said gas storage reservoir, a check valve therein, a connection leading from said storage reservoir to the interior of said cylinder, and a gas and air mixer in said last mentioned connection.

RICHMOND LEVERING.
